UNITED STATES PATENT OFFICE.

LAWRENCE J. McCARTHY, OF CHICAGO, ILLINOIS, ASSIGNOR TO SEARS, ROEBUCK AND CO., OF CHICAGO, ILLINOIS, A CORPORATION OF NEW YORK.

FINGER-PROTECTOR.

1,359,717.

Specification of Letters Patent. Patented Nov. 23, 1920.

Application filed May 22, 1918. Serial No. 235,939.

To all whom it may concern:

Be it known that I, LAWRENCE J. McCARTHY, a citizen of the United States, residing at Chicago, in the county of Cook and State of Illinois, have invented certain new and useful Improvements in Finger-Protectors, of which the following is a specification.

This invention relates to devices for protecting the finger tip from chafing or other injury while sticking pins through paper, and performing similar operations, also to facilitate the turning, buckling or picking up of leaves of paper, currency and the like.

Among the salient objects of the invention are to provide an exceedingly simple construction, to make the device very flexible so as to conform to the finger, to provide convenient and simple means for securing the protector to the finger and for adjusting the protector to fingers of different sizes, and, in general, to make the device thoroughly effective in operation.

In the accompanying drawings, Figure 1 is a perspective view illustrating my improved finger protector and the method of using the same. Fig. 2 is a lower side view of the said protector, extended or flattened out as when in storage or transportation. Fig. 3 is a longitudinal central sectional view of the device.

The device comprises an elongated body 1 of a width approximating the width of a finger, and two straps 2 and 3 for securing the body to the finger. The straps 2 and 3 extend from opposite sides of the body 1 so as to lie at opposite sides of the finger, the body 1 extending longitudinally of the finger. The body and the straps are formed integral with each other, being herein shown as cut from a composite sheet of flexible material. Said sheet consists of a backing *a* of cloth or other textile material and a facing *b* of rubber, said backing and facing being vulcanized together or otherwise made substantially integral.

If desired, the face of the body 1 may be roughened in any suitable way, as by means of corrugations *c*, to increase the friction between the body and a sheet of paper to be moved.

The ends of the straps 1 and 2 are adapted to be secured together without a buckle or other extraneous uniting means. The strap 2 is provided with a plurality of slots

4 each adapted to receive the end of the strap 3. The side edges of the strap 3 have pairs of notches 5 and 6. The end portion 7 of the strap is adapted to be forced through either of the slots 4 until the notches 5 engage with the opposite ends of the slots 4 to secure the straps together. Similarly, the portion 8 of the strap 3 is adapted to be forced through either of the slots 4 until the notches 6 engage with the opposite ends of the slots 4. Thus, by means of the slotted strap 2 and notched strap 3, the body 1 may be conveniently and quickly secured to fingers of various sizes.

The textile backing material *a* serves the double purpose of preventing the rubber facing *b* from stretching out of shape, and acts as a stiffening means preventing displacement of the notched strap from the slotted strap.

It will be seen that I have provided a device of the type specified which is exceedingly simple in construction, inexpensive to make, readily adjustable to fingers of various sizes, yieldable to different shapes of fingers and hence comfortable in use, and effective in the performance of its functions.

As indicated in Figs. 2 and 3, when the straps 2 and 3 are disengaged from each other, the protector assumes a flat or plane condition, and hence occupies very little space in storage and transportation.

I claim as my invention:—

1. A finger protector having, in combination, a body arranged to extend lengthwise of a finger, and two straps extending from opposite sides of the body, said body and straps being formed from an integral flexible sheet comprising a textile backing and a rubber facing, the face of the body being corrugated, one of the straps having a slot therein and the edges of the other strap being notched, the slot in the first mentioned strap being adapted to receive the notched portion of the second mentioned strap and hold the protector on a human finger, said straps and body being adapted to assume a flat condition when the straps are disengaged from each other.

2. A finger protector having, in combination, a body and two straps, said body and straps being formed from an integral flexible sheet comprising a textile backing and a rubber facing, one of the straps having a slot therein and the other strap being

- notched, the second mentioned strap being adapted to enter the slot formed in the first mentioned strap until the notches of the second mentioned strap engage with the opposite ends of the slot to secure the straps together in embracing relation to the finger, said straps and body being adapted to assume a flat condition when the straps are disengaged from each other.
- 10 3. A finger protector having, in combination a body and two straps extending from opposite sides of the body, said body and straps being formed from an integral flexible sheet comprising a textile backing and a rubber facing, said straps being adapted to interengage and thereby secure the

straps together in embracing relation to the finger.

4. A finger protector having, in combination, a relatively large body portion and two relatively narrow straps extending from either side of said body portion, said straps and body portion being formed from an integral sheet composed of a rubber facing and a textile backing, one of said straps having a slot therein and the other strap having a notch therein, said straps being adapted to interengage behind a finger.

In testimony whereof I have hereunto set my hand.

LAWRENCE J. McCARTHY.
